(57) **CLAIM**

The ornamental design for an end plate assembly for a blind system, as shown and described.

DESCRIPTION

FIG. 1 is a front perspective view of the end plate assembly for a blind system of the present invention;

FIG. 2 is a rear perspective view thereof;

FIG. 3 is a front view thereof;

FIG. 4 is a rear view thereof;

FIG. 5 is a top view thereof;

FIG. 6 is a bottom view thereof; and,

FIG. 7 is a right side view thereof with the left side view being a mirror image thereof.

The broken lines in the drawings depict portions of the article that form no part of the claimed design.

1 Claim, 6 Drawing Sheets
